UNITED STATES PATENT OFFICE

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY

MINE CAR

Application filed May 22, 1925. Serial No. 32,094.

Reference is had to the accompanying drawings which illustrate the preferred form of the invention, though it is to be understood that the invention is not limited to the exact 5 details of construction shown and described, as it is obvious that various modifications thereof within the scope of the claims will occur to persons skilled in the art.

In said drawings:

10 Fig. 1 is a side elevation, partly broken away, of a mine car constructed in accordance with this invention;

Fig. 2 is a top plan view of the mine car shown in Fig. 1;

15 Fig. 3 is a transverse section taken on the line 3—3 of Fig. 2; and

Fig. 4 is a partial transverse section of a mine car of modified construction.

It is an object of this invention to provide 20 a mine car of improved construction having journal boxes directly supporting portions of the floor. It is also an object of this invention to provide an improved means for bracing the sills of a mine car in which the axles pass 25 through the sills and it is also an object of this invention to provide an improved means for bracing the floor of a mine car of the type in which portions of the floor are on different levels.

30 With these and other objects in view, a mine car constructed in accordance with this invention, comprises as shown in the drawings, sills 1 of Z-shape extending from end to end of the car and having their webs 2 placed vertically and the flanges placed horizontally, the top flanges 3 projecting outwardly and the bottom flanges 4 projecting inwardly and being of greater width than the top flanges 3. The bottom flanges 4 are 35 joined by a plate 5 secured to the flanges 4 by rivets 6 and forming the center floor portion of the car. The plate 5 ends short of the webs 2 of the sills 1 so that when the plate 5 is moved transversely of the car into contact 40 with the web 2 of one of the sills 1 the opposite edge of the plate 5 will be free of the flange 4 of the other sill 1 and may be moved past the outer edge of the flange 4 thus permitting of the insertion and removal of the 45 plate 5 in either assemblage or replacement.

To the webs 2 of the sills 1 journal boxes 7 are secured by bolts 8 which engage in openings in the webs 2 of the sills 1 and flanges 9 of the journal boxes 7 which contact with the webs 2. Flanges 10 of the journal boxes 55 7 bear against the bottom surfaces of the top flanges 3 of the sills 1.

To the top flanges 3 of the sills 1, of the construction shown in Figs. 1 to 3, are secured horizontal outwardly projecting plates 60 11 forming the side floor portions of the car and resting upon the journal boxes 7. The plates 11 have formed integral therewith upwardly bent portions forming the sides 12 of the car. The car sides 12 are finished with 65 rolled-over portions forming reinforced upper edges 13 for the sides.

The plates 11 are provided with openings 14 which receive the upper portions of wheels 15 carried by axles 16 which are mounted in 70 the journal boxes 7 and pass through openings in the webs 2 of the sills 1 and above the plate 5 forming the center portion of the car floor. The openings 14 are covered by wheel hoods 17 secured to the plates 11 by 75 rivets 18, the heads of the rivets adjacent the journal boxes 7 being received in recesses formed in the journal boxes.

The portions of the axles 16 between the sills 1 are covered by axle housings 19 of 80 substantially an inverted U-shape with outwardly projecting flanges 20 secured to the plate 5 by rivets 21 and adjacent rivets 6. Toward the ends, the housings 19 decrease in width and increase in height and at the 85 ends are formed with outwardly projecting vertical flanges 22 secured to the webs of the sills by rivets 23 and with outwardly projecting horizontal flanges 24 which overlap the plates 11 and top flanges 3 of the sills 1. 90 and are secured thereto by the rivets 25 which secure the plates 11 and top flanges 3 together at that point, the heads of the rivets 25 fitting into recesses formed in the journal boxes 7.

At the center of the car the webs 2 of the sills 1 are connected by a tie 26 formed of a flanged plate having a horizontal flange 27 secured to the plate 5 by rivets 28 and a vertical flange 29 having a turned-over top 100

edge 30 and laterally projecting flanges 31 at its ends which are fastened to the webs 2 of the sills 1 by rivets 32. Angle braces 33 riveted to the sill webs 2 and the vertical flange 29 aid in securing the tie 26 to the sills 1.

To aid in supporting the load on the side floor portions braces 35 are provided which are bent to conform to the shape of the plates 11 and are riveted to the car sides 12 and the side floor portions and extend at an angle from about the longitudinal axis of the side floor portions toward the bottoms of the webs 2 of the sills 1 and are then bent upwardly, 10 contacting with the outer faces of the sill webs 2 and being riveted to the webs. The braces 35 are placed at the car ends, at the center tie 26 and adjacent the axle housings 19 so that any tendency of the braces 35 to 15 twist the sills 1 will be resisted by the car ends, the center tie 26 and the axle housings 19 which serve to secure the sills in relatively 20 fixed positions.

It will be noted that in a car constructed in accordance with this invention the plate 5 forming the center portion of the floor may be removed for repairs or replaced by removing the rivets securing the plate 5 to the sills 1, axle housings 19 and ties 26; that the 25 side portions of the floor are adequately braced by the braces 35 secured to the sills 1; and that any tendency of the braces 35 to distort the car will be overcome by the manner in which the sills are connected together. 30 It will also be noted that the axle housings 19 and tie 26 will serve as compression members and prevent distortion of the car body by the 35 load on the center portion of the car.

In the modified construction shown in Fig. 40 the plates 40 forming the side floor portions incline upwardly from the sills 1 and the top flanges 3 of the sills 1 are bent to conform to the inclination of the plates 40. In this construction, the braces 41 are in contact with 45 and fastened to the plates 40 forming the car sides 42 and side floor portions from the upper edges of the car sides 42 substantially to the sills 1 and are then bent downwardly to engage the outer faces of the sill webs 2 substantially to the bottom flanges 4 of the 50 sills 1 and are then bent outwardly and upwardly into contact with the portions of the braces 41 secured to the side floor portions at substantially the longitudinal axes 55 of the side floor portions, both portions of the braces 41 being secured to the plates 40 by the same rivets 43.

What is claimed is:

1. In a mine car, sills having vertical webs and inwardly and outwardly projecting flanges, a central floor portion secured to said inwardly projecting flanges, side floor portions secured to said outwardly projecting flanges, braces for said side floor portions se-

cured to said sill webs and axle housings connecting said sill top flanges.

2. In a mine car, sills having vertical webs and outwardly projecting flanges, side floor portions secured to said flanges, braces for said side floor portions secured to said sill webs and inverted channel-shape members connecting said webs and flanges. 70

3. In a mine car, sills having vertical webs and outwardly projecting flanges, side floor portions secured to said flanges, braces for said side floor portions secured to said sill webs and journal boxes secured to said sill webs and supporting said side floor portions. 75

4. In a mine car, sills having vertical webs and outwardly projecting flanges, side floor portions secured to said flanges, braces for said side floor portions secured to said sill webs, means connecting said sill webs and journal boxes secured to said sill webs and 80 supporting said side floor portions. 85

5. In a mine car, Z-shape sills having vertical webs and outwardly projecting top flanges, side floor portions secured to said top flanges, braces for said side floor portions secured to said webs, journal boxes secured to said sill webs and supporting said side floor portions, axles mounted in said journal boxes and passing through openings in the sill webs and axle housings connecting said sill webs and top flanges. 90 95

6. In a mine car, Z-shape sills having outwardly projecting top flanges, vertical webs and inwardly projecting bottom flanges, side floor portions secured to said top flanges, a center floor portion secured to said bottom flanges, braces for said side floor portions secured to said sill webs, journal boxes secured to said sill webs and supporting said side floor portions, axles mounted in said journal boxes and passing through openings in said sill webs and above said center floor portion and axle housings connecting said sills and center floor portion. 100 105

7. In a mine car, sills having inwardly projecting bottom flanges and a plate forming the center floor portion carried by said flanges, said plate being of less width than the distance between a sill web and the flange of the other sill. 110 115

8. In a mine car, sills having vertical webs and inwardly projecting bottom flanges, a floor portion carried by said flanges, bracing means connecting said sill webs, said bracing means being connected to said floor portion and axle housings connecting said floor portion and sills. 120

9. In a mine car, flanged sills having vertical webs, floor portions on different levels connected to said sill flanges, channel-shape bracing means connecting said sills and said lower floor portion, bracing means connecting said sill webs and said higher floor portions and journal boxes secured to said sills and supporting said higher floor portions. 125 130

10. In a mine car, sills having vertical webs and outwardly projecting top flanges, plates secured to said sill flanges and projecting outwardly to form side floor portions of the car, portions of said plates being bent upwardly to form car sides, bracing means for said plates secured to said car sides and side floor portions of said plates and to the outer faces of said sill webs and channel-shape members connecting said sill webs and flanges. 10
11. In a mine car, sills having vertical webs and outwardly projecting flanges and axle housings connecting said webs and flanges. 15
12. In a mine car, Z-shape sills having vertical webs, side floor portions secured to said sill top flanges, braces for said side floor portions secured to sill webs, axles passing through openings in said sill webs and axle 20 housings connecting said sill webs and top flanges. 20
13. In a mine car, Z-shape sills having vertical webs, floor portions secured to said sill top flanges and journal boxes secured to said 25 sill webs and supporting said floor portions. 25
14. In a mine car, Z-shape sills having vertical webs, side floor portions secured to said sill top flanges, a center floor portion secured to said sill bottom flanges, braces for 30 said side floor portions secured to said sill webs, axles passing through openings in said sill webs and above said center floor portion and axle housings connecting said sills and center floor portion. 30
15. In a mine car, Z-shape sills having vertical webs, side floor portions secured to said sill top flanges, a center floor portion secured to said sill bottom flanges, braces for said 35 side floor portions secured to said sill webs and channel-shape bracing means connecting said sills and said center floor portion. 40
16. In a mine car, sills having vertical webs and outwardly projecting flanges, side floor portions secured to said flanges, means 45 connecting said sill webs and journal boxes secured to said sill webs and supporting said side floor portions. 45
17. In a mine car, Z-shape sills having vertical webs and outwardly projecting top 50 flanges, side floor portions secured to said top flanges, journal boxes secured to said sill webs and supporting said side floor portions, axles mounted in said journal boxes and passing through openings in the sill 55 webs and axle housings connecting said sills. 55
18. In a mine car, Z-shape sills having outwardly projecting top flanges, vertical webs and inwardly projecting bottom flanges, side floor portions secured to said top flanges, a 60 center floor portion secured to said bottom flanges, journal boxes secured to said sill webs and supporting said side floor portions, axles mounted in said journal boxes and passing through openings in said sill webs and 65 above said center floor portion and axle hous- 65
- ings connecting said sills and center floor portion. 70
19. In a mine car, Z-shape sills having vertical webs, side floor portions secured to said sill top flanges, journal boxes secured to said sills and supporting said side floor portions, axles mounted in said journal boxes and passing through openings in said sills and axle 75 housings connecting said sill webs and top flanges. 75
20. In a mine car, Z-shape sills having vertical webs, side floor portions secured to the sill top flanges, a center floor portion secured to the sill bottom flanges, journal boxes secured to said sills and supporting said side floor portions, axles mounted in said journal boxes and passing through openings in said sills and above said center floor portion and axle 80 housings connecting said sills and center floor portion. 80
21. In a mine car, Z-shape sills having vertical webs, side floor portions secured to the sill top flanges, a center floor portion secured to the sill bottom flanges, journal boxes carried by said sills and supporting said side 85 floor portions and bracing means connecting said sills and center floor portion. 85
22. In a mine car, flanged sills, side and center floor portions secured to the sill flanges, braces for said side floor portions 90 secured to said sills and axle housings connected to flanges of said sills. 90
23. In a mine car, sills having oppositely disposed flanges, floor portions secured to said sill flanges, means secured to said sills 100 and supporting some of said floor portions and axle housings connected to flanges of said sills. 100
24. In a mine car, sills having oppositely disposed flanges, floor portions secured to said sill flanges and oppositely disposed with respect to said sills, means secured to said sills and supporting some of said floor portions and axle housings connected to flanges of said sills. 105
25. In a mine car, flanged sills, side and center floor portions secured to said sill flanges, axle housings connecting flanges of said sills and journal boxes supporting said side floor portions. 110
26. In a mine car, sills having oppositely disposed flanges, oppositely disposed floor portions secured to said sill flanges and journal boxes secured to said sills and supporting some of said floor portions. 115
27. In a mine car, sills having oppositely disposed flanges, and a floor portion carried by said flanges, said floor portion being adapted to be dropped between said flanges. 120
28. In a mine car, sills having oppositely disposed flanges, side and center floor portions secured to said flanges, bracing means secured to said sills and to said floor portions and journal boxes secured to said sills and supporting said side floor portions. 125
- 130

29. In a mine car, sills having oppositely disposed flanges, side and center floor portions secured to said flanges, journal boxes secured to said sills and supporting said side floor portions and axle housings connecting said sills and said center floor portion. 70
30. A mine car including sills, a central floor portion attached to the sills, side floor portions also attached to the sills and disposed above the plane of the central floor portion, and journal boxes connected with and supporting the sills and engaging beneath the side floor portions and supporting the latter. 75
31. A mine car including sills, floor portions attached thereto and projecting laterally beyond the sills, and laterally projecting journal boxes connected directly to the sills and supporting said floor portions. 80
32. In a mine car, a car axle housing having flanges for attachment to the car side floor portions. 85
33. In a mine car, a car axle housing having flanges for attachment to the car side and center floor portions. 90
34. In a mine car, a car axle housing having flanges for attachment to the car sills and side and center floor portions. 95
35. In a mine car, a pressed car axle housing of channel-shape having flanges for attachment to the car side floor portions. 100
36. In a mine car, axles, a floor portion below said axles, floor portions in a plane relatively higher than said axles and an axle housing connecting said floor portions. 105
37. In a mine car, axles, a floor portion below said axles, floor portions in a plane relatively higher than said axles and an inverted channel-shape axle housing connecting said floor portions. 110
38. In a mine car, a floor portion, sills extending from said floor portion to a higher plane, side floor portions connected with the upper portions of said sills and a channel-shape member connecting said floor portions and sills. 115
39. In a mine car, a pressed channel-shape tie member having laterally projecting flanges for attachment to the car center floor portion and longitudinally projecting flanges for attachment to the car side floor portions. 120
40. In a mine car, a pressed channel-shape tie member having longitudinally projecting flanges for attachment to the car sills and side floor portions. 125
41. In a mine car, a pressed channel-shape tie member having laterally projecting flanges for attachment to the car sills and longitudinally projecting flanges for attachment to the car sills and side floor portions. 130
42. In a mine car, a pressed channel-shape tie member having laterally projecting flanges for attachment to the car sills and
